UMBRELLA FERRULE PINNING MACHINE

Frank De Bella, Newark, and Thomas F. De Bella,
Union, N. J.

Application November 15, 1946, Serial No. 709,952

12 Claims. (Cl. 1—1)

1

This invention relates to machines for mounting or affixing tips, end pieces or ferrules to the ends of umbrella shanks, canes or the like, and is an improvement on the structure shown and described in Pat. 2,285,380, dated June 2, 1942.

One object of the invention is the provision of a ferrule pinning machine which is adapted to accommodate various sizes of ferrules by but a slight adjustment and one in which the length of wire cut off may be adjusted to correspond to the diameter of the ferrule.

Another object of the invention is the provision of an improved wire pin cutting and feeding mechanism for such machines.

Another object is to produce a machine of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, wherein similar reference characters are used to denote corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

In carrying out the objects of the present invention it was found advantageous to provide a lower portion of the device which is adapted to be suitably secured to the bedplate of a press and an upper portion carried by the press plunger. The lower portion of the device preferably includes a socket for holding the ferrule and umbrella shank below a rotatable wire cutter, operable for cutting the wire upon the downward stroke of the plunger which carries the upper portion of the device, the ferrule being pinned upon said downward stroke and a new length of wire fed upwardly upon the return upward stroke of the press.

The invention will be more clearly understood from the following detailed description and accompanying drawings, in which—

Figure 1 is a front elevational view of a ferrule pinning device made in accordance with the present invention;

2

Figure 2 is a horizontal sectional view taken along line 2—2 of Figure 1;

Figure 3 is a top plan view of the device looking from the top of Figure 1;

Figure 4 is a view looking from the rear of Figure 3;

Figure 5 is a longitudinal sectional view taken along line 5—5 of Figure 1;

Figure 6 is a fragmental sectional view taken on line 6—6 of Figure 2 and showing the device just prior to the wire cutting operation;

Figure 7 is a similar view with the press plunger in lower position.

Referring now to the drawings in detail, the 15 numeral 10 indicates the stationary bed plate of a power press or foot press having an up and down reciprocating plunger 11. Secured to the bed plate 10 by any suitable means as for instance clamps 12 is a base block 13 upon which 20 the lower portion of the device is suitably supported.

Carried by the central front portion of the base block 13 is a slideway 14 to which are secured front plates 15 by means of screws 16. Slidably 25 mounted between the sides of the slideway 14 and plates 15 is a lower socket portion 17 having a V-shaped cutout 18 best shown in Figures 1, 2 and 5. The socket portion 17 is vertically adjustable by means of a screw 19 centrally located at the bottom of the slideway 14. The socket portion 17 is pressed against the screw 19 by means of springs 20 which bear against the top of said portion 17 and an upper socket portion which is in the form of a plate 21 secured in place by 30 screws 22. The plate 21 has a central arcuate cut-out 23 which with the V-shaped cutout 18 forms a socket 24 for the reception of the tip or ferrule 25 to be pinned to the end of the shank 26 of an umbrella 27.

40 The base block is provided with a vertical opening 28 the upper portion of which is screw threaded as at 29 to receive the screw threaded end 30 of a bushing 31. Rotatably mounted on said bushing 31 is a disk 32 having ratchet teeth 33 and provided with radially spaced apart holes 34 equal in number to the number of teeth 33. The lower portion 35 of the disk 32 bears against the top surfaces of plate 21 and together with a hardened bushing 36 in the base block 13 forms wire 45 cutting means. The said portion may if desirable be in the form of a separate hardened disk secured to the disk 32 or the two disks may be integral as shown. Where the disks are separate, the lower disk 35 will be provided with holes in 50 continuation of the holes 34.

Passing through the bushing 31 is a rod 37 which at its upper end has a screw threaded portion 38 which enters a screw threaded opening 39 in a shaft 40 having a lower screw threaded reduced portion 41 screw threadedly secured to a carrier head or block 42. The rod 37 is locked in place against the reduced shaft portion 41 by means of a nut 43. The upper part of the shaft 40 is engagedly secured to, or carried by the press plunger 11. The block 42 is provided near the rear thereof with a pair of spaced apart guide rods 44 which have sliding engagement in holes 45 in the base block 13. Suitable lubricating cups 46 are provided for lubricating the said rods as they travel up and down in the holes 45. The carrier head or block 42 has a roller 47 rotatably secured thereto by means of a stud 48, the said roller being in engagement with a cam surface 49 at the top of a plate 50 secured to a brake arm 51 by means of a screw 52. The brake arm 51 is rotatably mounted on the bushing 31 beneath a head 53 on said bushing and is provided with an opening 54 in which there is slidably mounted a pawl 55 having a hole 56 in which is located a compression spring 57 which is held in place by means of a plate 58 secured to the brake arm 51 by one or more screws 59. The spring 56 normally maintains the pawl 55 in contact with one of the teeth 33. The brake arm 51 is under control of a spring 60 anchored at one end to a stud 61 on said arm and at the opposite end on a hook 62 secured to the base block 13 by screws 63. (See Fig. 4.) A second pawl 64 engages one of the teeth 33, said second pawl being spaced 90° from the pawl 55 and slidably mounted in a block 65 secured to the base block 13 by screws 66. The said pawl 64 is provided with a hole 67 in which there is located a coiled tension spring 68 which exerts a pressure against the said pawl and a plate 69 to maintain the pawl in engagement with the toothed disks 32. The plate is secured to the block 65 by screws 70 and 71.

The bottom of the rod 37 has a reduced portion 72 which in turn has a reduced threaded end 73 for the reception of a cylinder 74 which forms a part of a wire feeding mechanism, a description of which follows.

Pins 75 for pinning ferrule 25 to stem 26 at 76 (see Fig. 5) are cut from a wire 77 supplied to the device from a source not shown in the drawings. The wire feeding mechanism includes a guide plate 78 secured to the underside of the base block 13 by screws 79. The said guide plate is provided with an opening 80 through which the wire passes upwardly and is normally frictionally held against by a flat spring 81 secured to the said plate 78 by a screw 82. The base block 13 is provided with a slideway 83 at the left side thereof as viewed in Figs. 6 and 7 in which is slidably mounted a wire feed bracket 84 which is provided at one end with a hole 85 which embraces the reduced rod portion 72. Intermediate the end thereof the bracket 84 is perforated as at 85-85 for the passage of the wire 77 therethrough. A plate 86 movably supported at one end on a screw 87 is frictionally maintained at its opposite end against the wire 77 by means of a spring 88 wound about said screw and exerting a pressure between the said plate and a washer 89 an said screw 87. As shown in Figures 1, 4, 5 and 6, the device is in a position after an idle movement of the press to bring the roller 47 into position to contact the cam surface 44 for actuating the device for cutting the wire to form a pin 75.

The operation of the device is as follows:

Initially, wire 77 is threaded upwardly through the opening 80, 85 and bushing 36 into an opening 34 to approximately the top of the toothed disk 33. The press is then actuated to move its plunger 11 downwardly, thus carrying with it the shaft 40, rod 37, head 42 and roller 47. The first part of this downward movement is an idle movement on the shoulder 90 formed at the juncture of the rod 37 and its reduced portion 72 moves towards the top surface 91 of the bracket while the cylinder 74 moves away from the bottom surface 92 of said bracket. During the next part of the movement, the roller 47 strikes against the cam face 44 and moves the brake arm and its pawl 55 to the dot and dash position shown in Figure 2, thus rotating the toothed disk 32 the distance of one tooth against the tension of the spring 60 and spring pressed pawl 64. During the said rotation, the pin 75 has been cut from the wire 77 by the shearing action between the bushing 36 and the disk portion 35, the said pin being carried the angular distance between two teeth 33 or holes 34. During the part of the downward movement just described and upon further downward movement of the moving parts above enumerated, the shoulder 90 contacts the bracket surface 91 and moves said bracket down, the wire 77 meanwhile being held against downward movement by the spring 81 thus permitting the loosening of the tension between the said wire and spring pressed plate 86. Upon the upward stroke of the press plunger, a shoulder 74a formed by top of the cylinder 74 contacts the bottom surface 92 of the bracket 84 and carries same upwardly. This upward movement of the bracket 84 causes the spring 81 to release the wire 77 and the plate 86 to press against said wire and feed same upwardly into the disk 32 a sufficient distance for another pin length. The above operation is repeated until the disk 32 has been moved through an arc of 90° after which the umbrella or cane to be operated upon is inserted into the socket 24. With the umbrella or cane in position and upon the next downward stroke of the press a pin-like tool 93 carried in a chuck 94 on head 42 will push the pin 75 into the aligned openings 95 and 96 respectively of the ferrule and umbrella or cane tip. The brake arm 51 is returned to normal position by spring 60 upon the upward stroke of the press when the roller 47 is free of the cam 49. The amount of wire fed and consequent length of pin cut off may be adjusted by unscrewing or tightening the cylinder 74 on the threaded end 73 of the rod 37.

From the foregoing it will be seen that the present invention provides a highly effective device for pinning ferrules to the ends of umbrellas and for canes of various diameters.

It is apparent that the specific embodiment shown above has been given by way of illustration and not by way of limitation, and that the structure above described is subject to wide variation and modification without departing from the scope or intent of the invention, all of which variations and modifications falling within the scope of the appended claims or their mechanical equivalents are to be included in the present invention.

What is claimed is:

1. A ferrule affixing device, comprising a base, means on said base for supporting a ferrule to be affixed, a bushing on said base, a reciprocable carrier above said base carrying out an operative movement and a return movement, a step

by step rotatable disk above and in contact with the bushing and having a plurality of holes one for each step radially spaced from the center of the disk, said radial spacing being co-axial with the bushing when brought into alignment therewith, a device vertically reciprocable on said base for feeding wire through said bushing into an alined opening in the disk on said return movement, means for rotating the disk an angular distance equal to the distance between two holes therein for shearing off a portion of wire during the operative movement and carrying same to eventually be positioned above the ferrule, and a driving tool carried by the carrier for driving said sheared off portion into the ferrule on the operative movement of the carrier.

2. A ferrule affixing device, comprising a base, means on said base for supporting a ferrule to be affixed, a bushing on said base, a reciprocable carrier above said base carrying out an operative movement and a return movement, a rotatable toothed disk above and in contact with the bushing and having a number of holes therein equal to the number of teeth, said holes being radially spaced from the center of the disk the radial distance coinciding with the radial distance of the bushing from said center of the disk, means for releasably holding said disk against rotation, a pivotal arm co-axially mounted with the disk, a spring pressed pawl carried by said arm in engagement with the toothed disk, a device vertically reciprocable on the said base for feeding wire through said bushing into an opening in the disk on said return movement and for reciprocating said wire feeding device, means on the carrier and arm for rotating said arm and disk the angular distance between two teeth for shearing off a portion of wire during the operative movement and carrying said wire portion step by step to a position above the ferrule, a driving tool carried by the carrier for driving said wire portion into the ferrule during the operative movement of the carrier, and spring means for returning the said arm to normal position at the end of the return of said carrier.

3. A ferrule affixing device, comprising a base, means on said base for supporting a ferrule to be affixed, a bushing on said base, a reciprocable carrier above said base carrying out an operative movement and a return movement, a rotatable toothed disk above and in contact with the bushing and a number of holes therein equal to the number of teeth, said holes being radially spaced from the center of the disk the radial distance coinciding with the radial distance of the bushing from said center of the disk, means for releasably holding said disk against rotation, a pivotal arm co-axially mounted with the disk, a spring pressed pawl carried by said arm in engagement with the toothed disk, a device vertically reciprocable on the said base for feeding wire through said bushing into an opening in the disk on said return movement, means on the carrier for so reciprocating said wire feeding device, a roller on the carrier, a cam on the arm for contacting the roller on the operative movement of the carrier for rotating said arm and disk the angular distance between two teeth for shearing off a portion of wire and carrying same step by step to a position above the ferrule, a driving tool carried by the carrier for driving said wire portion into the ferrule during the operative movement of the carrier, and spring means for

returning the said arm to normal position at the end of the return movement of said carrier.

4. A device according to claim 1 wherein the ferrule supporting device is adjustably mounted on the base so as to accommodate ferrules of various diameters.

5. A ferrule affixing device, comprising a base, means on said base for supporting a ferrule to be affixed, a bushing on said base, a reciprocable carrier above said base carrying out an operative movement and a return movement, a wire cutting and carrying disk overlying the base and bushing and rotatable thereabout, a wire feeding device vertically reciprocable beneath said bushing and spaced at an angle to the ferrule supporting means, the said disk having openings therein adapted to be brought into alignment with the bushing and wire feeding device, means on the carrier for operating the wire feeding device on the return movement of the carrier to feed wire through the bushing into the disk and means associated with the carrier and disk or rotating the disk through an angle equal to the angular distance between two openings on the next operative movement of the said carrier to cut off the wire within the disk and carry same towards the position of the ferrule supporting device.

6. A ferrule affixing device, comprising a base, means on said base for supporting a ferrule to be affixed, a bushing on said base, a reciprocable carrier above said base carrying out an operative movement and a return movement, a wire cutting and carrying disk overlying the base and bushing and rotatable there about, a wire feeding device vertically reciprocable beneath said bushing and spaced at an angle to the ferrule supporting means, the said disk having openings therein adapted to be brought into alignment with the bushing and wire feeding device, means on the carrier for operating the wire feeding device on the return movement of the carrier, said wire feed operating means comprising a rod, and a shoulder near the bottom of said rod for contacting and moving the wire feeding device and wire carried thereby to feed a portion of the wire through the bushing into the disk to be cut off on the next operative movement of the carrier.

7. A ferrule affixing device, comprising a base, means on said base for supporting a ferrule to be affixed, a wire bushing on said base, a reciprocable carrier above said base carrying out an operative movement and a return movement, a cutting and carrying disk overlying the base and bushing and rotatable thereabout, a wire feeding device vertically reciprocable beneath said bushing and spaced at an angle to the ferrule supporting means, the said disk having openings therein adapted to be brought into alignment with the bushing and wire feeding device, means on the carrier for operating the wire feeding device on the return movement of the carrier, said wire feed operating means comprising a rod, a shoulder near the bottom of said rod for contacting and moving the wire feeding device and wire carried thereby to feed a portion of the wire through the bushing into the disk to be cut off on the next operative movement of the carrier, means on the carrier for rotating the disk through an angle equal to the angular distance between two openings on the next operative movement of the said carrier to cut off the wire within the disk and carry same towards the position of the ferrule supporting device, a tool carried by the carrier for driving a cut off portion of the wire

above the ferrule thereinto, and a second shoulder on the rod above the first mentioned shoulder for contacting and moving the wire feeding device free of the wire to the aforementioned position to be moved in wire feeding direction by the next return movement of the carrier.

8. A device according to claim 6 wherein the said shoulder is axially adjustable on the rod for moving the wire feeding device greater or lesser distances.

9. A device according to claim 7 wherein the first mentioned shoulder is axially adjustable on the rod for moving the wire feeding device greater or lesser distances.

10. A ferrule affixing device, comprising a base, means on said base for supporting a ferrule to be affixed, a bushing on said base, a reciprocable carrier above said base carrying out an operative movement and a return movement, a wire cutting and carrying disk overlying the base and bushing and rotatable thereabout, a plate secured to the base and provided with an opening in axial alinement with the bushing, a bracket slidably mounted in the base above said plate and provided with an opening in axial alinement with the bushing and opening in the plate for permitting a wire to pass through said alined openings, a spring on the plate frictionally maintaining the said wire against the opening in said plate, a spring pressed plate on the bracket in engagement with the wire for frictionally holding same against the bracket, a rod secured to the carrier, a reduced portion on the rod passing through the bracket and forming a shoulder thereabove, an enlarged cylinder below the reduced portion and 35

forming a shoulder below the bracket, the upper shoulder adapted to contact the bracket to slide same down free of the wire on the operative movement and the lower shoulder contacting the said bracket on the return movement to slide said bracket to feed the wire into the wire cutting disk to be cut off upon the next operative movement of the carrier, and means on the carrier for driving the cut off wire into the ferrule 10 upon said operative movement of the carrier.

11. A device according to claim 10 wherein the cylinder is adjustably mounted below said reduced portion.

12. A ferrule affixing device, comprising a base, 15 means on said base for supporting a ferrule to be affixed, a reciprocable carrier above said base carrying out an operative movement and a return movement, a wire cutting device rotatably supported on the base, a wire grasping and feeding device below the wire cutting device, means 20 associated with the wire cutter for rotating same, means on the carrier for actuating the wire cutter rotating means on the operative movement of the carrier, a wire feeding device-positioning and 25 feed actuating member carried by the carrier for freeing the wire feeding device from the wire and positioning same for contact with the feed actuating member so that said member will actuate said wire feeding device to feed wire into the wire 30 cutting device to be cut upon the next operative movement of the carrier, and means on the carrier for driving a cut off wire portion into the ferrule on an operative movement of the carrier.
